LOOSE LEAF BINDER

Clarence D. Trussell, Poughkeepsie, N. Y., assignor to Trussell Manufacturing Company, Poughkeepsie, N. Y., a corporation of New York

Application November 10, 1938, Serial No. 239,792

5 Claims. (Cl. 129—24)

The invention here disclosed relates to loose leaf binders and particularly to those of the type disclosed in the Trussell Patents 1,180,342, 1,468,846, 1,800,268 and 1,953,981, in which "triggers" or other special devices are provided for effecting actuation of the toggle plates carrying the cooperating ring elements.

The objects of the present invention are to provide simple, efficient and inexpensive mechanism for effecting the ring closing movements of the toggle plates, in a form which may be readily combined with such plates, without however impeding or in any way interfering with proper free operation of the plates.

15 Other desirable objects of the invention and the novel features of construction, combinations and relations of parts by which all such objects are attained will appear and are set forth in the following specification.

20 The drawings accompanying and forming part of the specification illustrate definite practical embodiments of the invention. The structure of the invention however may be modified and changed as regards this particular disclosure, all 25 within the true intent and broad scope of the claims.

Fig. 1 is a plan view of a complete loose leaf binder metal incorporating features of the invention, showing the rings in closed position.

30 Figs. 2 and 3 are enlarged broken longitudinal sectional views showing the parts respectively in the ring closed and ring open positions.

Figs. 4 and 5 are cross-sectional details on lines 4—4 and 5—5 of Fig. 2, illustrating relation of 35 the ring closing trigger and the ring opening trigger respectively in the ring closed condition of the binder.

Figs. 6 and 7 are similar views on lines 6—6 and 7—7, Fig. 3, showing the same parts in the 40 ring open position of the binder.

Fig. 8 is a perspective view of the ring closing trigger or lever.

The binder illustrated consists in general of a spring back plate 10, having inturned edges 11, 45 forming channels in which are engaged the outer edges of the toggle plates 12, carrying the companion ring elements, hooks or prongs 13, the latter operating up through slots 14, in the edges of cover plate 15, which is closed down about the 50 edges of the back plate at 16.

The ring opening trigger is designated 17, at the right hand end of the binder metal, Figs. 1, 2 and 3 and the ring closing trigger is designated 18, at the opposite left hand end of the 5 structure. The exposed portions of the two trig-

gers, for the sake of symmetry may be alike as indicated in Fig. 1, or if desired, particularly for purposes of identification, they may be of distinctive appearance or differently marked in some manner. They are both shown as formed of sheet metal, doubled and downwardly folded to provide a smooth top lever portion with substantially parallel sides 19.

The ring opening trigger 17 is shown as having a cross bar 20, secured in transverse notches 21, in the downwardly folded sides of the lever, said cross bar resting at its ends at 22, on top of the tongues 23, at the ends of the toggle plates and having an intermediate portion 24, which can swing down through the notched portion 25, in the end of the toggle plates, between the end lugs or tongues 23. The plates are shown as having a deeper notch 26, at the center receiving the folded portions of the lever forward of the cross bar 21. The lower ends of these forward portions of the trigger are shown as having hook extensions 27, engaging the undersides of the ring plates, near the center meeting edges of the same. Figs. 2 and 3, in particular show how the opening lever 17, rests loosely on top of the end, outer edge portions 23, of the toggle plates being retained in this position by the cover plate 15, which has the slot 28, receiving the downwardly folded portions 19, of the lever and which slot, while sufficient in extent to permit full leverage movement of the trigger, will prevent the trigger from dropping back off the end of the plates.

When the rings are closed and the toggle plates bent downwardly as in Figs. 2 and 5, the hooked forward ends 27, of the trigger, caught beneath the central portions of the plates, will rock and hold the trigger tipped forwardly, with the exposed handle portion standing up as in Fig. 2. This trigger thus shows by its raised position that it is the one to be pressed for opening the rings. As it is pressed downwardly to the Figs. 3, 7 position, the hooked forward ends 27, acting upwardly against the central portions of the toggle plates adjacent the opposing edges, rock these plates upwardly to carry the ring prongs to the open position. The cutout or notched central portions 25, 26, in the end of the toggle plates provide clearance, enabling these plates to rock upwardly from the lowermost (Fig. 5) to the uppermost positions (Fig. 7) even though the cross bar of the trigger actually rocks at 22, over the upper outer edge portions of the plates. Thus while the trigger is supported on top of the plates, the clearance notches in the ends of the plates enable

the latter to swing freely up and down past the end of the trigger.

The ring closing trigger 18, like the opening trigger 17, is simply loosely engaged over the ends of the toggle plates and has portions engaging the edge and intermediate portions of the plates at opposite sides of the same. The parts which engage the edge portions of the plates however, engage them at the underside and the parts engaging the intermediate portions of the plates engage them at the upper side, thus to enable such closer to rock the adjoining edge portions of the plates downwardly in the ring closing direction.

In the form here shown, the substantially parallel sides 19 of the closing trigger are arched at 29, to overstand the reduced width tongue portions 30, on the ends of the toggle plates, the sides 31, of such arch projecting downwardly through the slots or notches 32, in the ends of the plates and carrying at the forward end of the trigger lateral extensions 33, engaging beneath the edge tongues 34 of the plates. These sides of the arch also carry at an intermediate point in the length of the trigger, the inwardly struck lugs 35, which engage beneath the end tongues 30, on the central portions of the plates, thus to enable the plates to retract this lever as they move downward in the ring closing direction.

The closing trigger, like the opening trigger, is not caught or secured to the plates, but is merely held loosely engaged over the ends of the plates by having the folded down sides of the same operate loosely in a confining and guiding slot 36 in the cover plate 15.

In the closed position of the rings with the toggle plates rocked downwardly, the closer is in the lowered position, Figs. 2 and 4. When the opener rocks the plates upwardly, the center tongues 30, engage the underside of the arch 29, which may be inclined as indicated in Fig. 8, thus to lift the closer to the upstanding inclined position shown in Fig. 3. In this raised relation, the closer indicates by its position that this is the trigger to be depressed to effect closing of the rings. Downward pressure on this raised trigger causes it to rock on lugs 33, against the under edge portions 32, of the plates and to press with lugs 37, back of the inclined arch 29, downward on the central tongue portions 30 of the plates, thereby to rock the plates downwardly and close the rings.

The toggle plates or bars, except for notches in the ends of the same, may be of the usual construction. The trigger levers are assembled by inserting the handle portions up through the guide slots 28, 36, in the cover plate and then placing the cover over the toggle plates, so that the levers will drop endwise into the notches in the ends of the plates, with the transversely projecting lugs 22 and 33, engaging over and underneath the edge portions of the plates and intermediate lugs or hooks 27, 35, engaging beneath the central portions of the plates. The cover can then be flanged down about the back plate to retain the parts in such relation. This method of simply engaging the triggers endwise over the plates simplifies assemblage and leaves the ring carrying plates free to quickly snap open and closed with slight pressure on the triggers. The triggers in this construction need not extend beyond the ends of the cover plate and hence need not add any to the overall dimensions of the ring metal.

Desirable leverage for the closer is provided in

the illustration by the two lugs 37, projecting downwardly from the folded sides, spaced back from the pivoting axis 33, at the forward end of the trigger and located to engage the plates close to the meeting edges of the same. Lugs 38 dependent from the folded sides, in back of these closing lugs act as abutments, in the upraised position of the trigger to hold it confined in the guide slots.

What is claimed is:

1. A ring metal for loose leaf binders, comprising cooperating spring tensioned toggle plates having open notches in the intermediate portion of the same at one end of the metal, a closer having an arched portion overstanding the intermediate edge portions of said plates and downward extensions disposed in said notches, laterally projecting lugs on said downward extensions engaging beneath said plates at the outer edge portions of the same and a cover plate having a slot above said notched portions of the toggle plates, said closer having an operating lever portion above said cover plate and a dependent portion loosely confined in said slot.

2. A ring metal for loose leaf binders, comprising cooperating spring tensioned toggle plates having open notches in the intermediate portion of the same at one end of the metal, a closer having an arched portion overstanding the intermediate edge portions of said plates and downward extensions disposed in said notches, laterally projecting lugs on said downward extensions engaging beneath said plates at the outer edge portions of the same and a cover plate having a slot above said notched portions of the toggle plates, said closer having an operating lever portion above said cover plate, and a dependent portion loosely confined in said slot, said arched portion of said closer being inclined relative to the longitudinal extent of the lever portion.

3. A ring metal for loose leaf binders, comprising cooperating spring tensioned toggle plates having open notches in the intermediate portion of the same at one end of the metal, a closer having an arched portion overstanding the intermediate edge portions of said plates and downward extensions disposed in said notches, laterally projecting lugs on said downward extensions engaging beneath said plates at the outer edge portions of the same and a cover plate having a slot above said notched portions of the toggle plates, said closer having an operating lever portion above said cover plate and a dependent portion loosely confined in said slot, said downward extensions of the arched portion having inwardly projecting lugs engaging beneath the intermediate portions of said toggle plates.

4. In a loose leaf binder, cooperating ring carrying toggle plates having open slots in the ends of the same at one end of the binder, a closer having an intermediate arched portion over the intermediate end portions of said plates and extensions disposed in said slots and engaged beneath the plates at the outer edges of the latter, dependent lugs at the rear of the arched portion engageable with the opposing edge portions of the plates at a point removed longitudinally of the binder from the line of engagement with the outer edge portions of the plates and a cover over said toggle plates having a slot through which the closer projects and by which said closer is rockingly held engaged as described with said slotted end portions of said plates.

5. A binder comprising cooperating prong carrying toggle plates having open notches in the

ends of the same at one end of the binder, a lever having an arched portion at one end engageable endwise in said open notches and an operating handle at the opposite end, relatively 5 widely spaced lugs projecting from the sides of said arched portion and bearing on the outer edge portions of the toggle plates beyond the notches therein at one face of said toggle plates, relatively closely spaced lugs on the sides of said arched 10 portion spaced away from the more widely separated lugs longitudinally of the lever and bearing on the adjoining edge portions of the toggle plates at the opposite face of said toggle plates, whereby pressure on the handle end of said lever will cause the same to fulcrum on the more widely spaced lugs to impart movement to the toggle plates in one direction through the medium of said more closely spaced lugs and a cover over said toggle plates and over the two sets of longitudinally spaced lugs engaging the opposite faces of said toggle plates, said cover having a slot therethrough in line with said arched portion of the lever and said arched portion extending loosely through said slot and whereby said lever is rockingly confined in position with said arched portion so entered in the notched ends of said toggle plates. 5
